(57) **CLAIM**

The ornamental design for a flask, as shown and described.

DESCRIPTION

FIG. 1 is a top plan view of a flask showing my new design;
FIG. 2 is a front elevation view thereof, the rear elevation view
being identical; and,

FIG. 3 is a bottom plan view thereof.

The broken line illustration in FIG. 3 shows environmental
structure and is not part of the design sought to be patented.
